CLAIM

The ornamental design for a mount for controller or the like, as shown and described.

DESCRIPTION

FIG. 1 is a bottom rear perspective view of a mount for controller or the like showing the claimed design;

FIG. 2 is a top front perspective view thereof;

FIG. 3 is a top view thereof;

FIG. 4 is a bottom view thereof;

FIG. 5 is a left side view thereof;

FIG. 6 is a right side view thereof;

FIG. 7 is a front view thereof; and,

FIG. 8 is a rear view thereof.

The broken lines in the figures show portions of the mount for controller or the like that form no part of the claimed design.
